UNITED STATES PATENT OFFICE.

UBALD HEBERT, OF MANCHESTER, NEW HAMPSHIRE, ASSIGNOR TO DRAPER CORPORATION, OF HOPEDALE, MASSACHUSETTS, A CORPORATION OF MAINE.

FILLING CLAMPING AND PARTING MEANS FOR LOOMS.

1,317,787.

Specification of Letters Patent.

Patented Oct. 7, 1919.

Application filed September 16, 1918. Serial No. 254,237.

To all whom it may concern:

Be it known that I, UBALD HEBERT, a citizen of the United States, residing at Manchester, county of Hillsborough, State of

5 New Hampshire, have invented an Improvement in Filling Clamping and Parting Means for Looms, of which the following description, in connection with the accompanying drawing, is a specification, like characters on the drawing representing like parts.

This invention relates to looms of the type wherein the running filling is replenished prior to complete exhaustion and in which a shuttle feeler is employed to restrain 15 the operation of the replenishing mechanism in case of an improperly boxed shuttle, and in which means are provided for clamping and parting the filling of the abandoned filling carrier, such means being usually supported by, or moving with, the shuttle feeler.

The invention is more particularly concerned with means for effecting the closing action of the filling clamping and parting means.

25 The object of the invention is to provide a mechanism which shall be simple in construction, easy to adjust, subject to as little wear as possible, and which shall effect the closing operation, preferably by a yielding action, of the filling clamping and parting means only when the shuttle containing the exhausted or substantially exhausted filling carrier is properly boxed at the transfer end of the loom.

35 These and other features of the invention will appear more fully from the accompanying description and drawings and will be particularly pointed out in the claims.

The invention in the preferred construction 40 disclosed is shown as embodied in a loom of the well known Northrop type having a rectilinearly movable shuttle feeler of the type disclosed in the patent to Davis No. 1,091,813 granted March 31, 1914. But it is 45 obvious that the invention in its broader aspects may be embodied in various specific forms of construction depending upon the character of filling replenishing loom to which it may be applied.

50 In the drawings,

Figure 1 is a transverse section of a portion of the automatic filling replenishing loom having one embodiment of the present invention applied thereto, the lay being

shown in full lines on back center and in 55 dotted lines on front center, and only those parts being shown which are necessary to an understanding of the invention;

Fig. 2 is a side elevation of a portion of the mechanism shown in Fig. 1 with the 60 shuttle feeler in its rearward position nearest the lay and with the filling clamping and parting means opened;

Fig. 3 is a front elevation partially in 65 vertical cross section of that portion of the loom shown in Fig. 1;

Fig. 4 is a detail in front elevation of a portion of the lay showing the bunter, positioner and trip mechanism;

Fig. 5 is a detail view on a larger scale 70 in side elevation showing the actuator and its support, the view being taken looking toward the left in Fig. 3;

Fig. 6 is a top plan view partially in horizontal cross-section of the construction 75 shown in Fig. 5.

The lay 1, transerrer 2 to transfer the fresh filling carriers, or in this case the bobbins 3, from the magazine or hopper 4 containing the supply of fresh filling carriers to 80 the lay as into the shuttle 5 when in the box at the transfer end of the loom, the controlling rock shaft 6 journaled on the front of the breast beam 7, are all of a construction familiar in the Northrop type of automatic 85 filling replenishing loom, the construction and operation of which is well known to those skilled in this art.

The remaining mechanism, except that 90 particularly involved in this invention is fully illustrated and described in the beforementioned patent to Davis and therefore needs no extended description.

In the construction illustrated the transerrer 2 is pivotally mounted on a hub 8 in 95 the hopper stand or other fixed portion of the loom and is provided with a depending arm 9 carrying a rectilinearly movable dog 10. A bunter 11 is rigidly secured to a shaft 12 journaled in a bearing block 13 mounted 100 on the face of the lay 1. When after the call for filling replenishment the shaft 12 is rotated to elevate the bunter 11 and the lay beats up the bunter striking the dog 10 effects the actuation of the transerrer to 105 transfer a fresh filling carrier 3 from the hopper 4 to the lay, all in a familiar manner.

The shuttle feeler 14 is formed on or car-

ried by a supporting arm 15 which depends from a sleeve 16 mounted to reciprocate rectilinearly and rotate upon the guide bar 17. This guide bar 17 is rigidly supported by 5 means of the set screws 18 in a bearing socket 19 formed in one arm 20 of a supporting bracket 21 fitting over and locked to the transfferer hub 8 by a set screw 22.

The shuttle feeler is actuated by a bell 10 crank lever 23 fulcrumed at 24 on the upper end of a second arm 25 projecting upwardly from the supporting bracket 21. One arm 26 of this bell crank lever is loosely connected to an arm 27 laterally projecting 15 from the sleeve 16 of the shuttle feeler support while the other arm 28 has a pin and slot connection with a link 29 connected at its lower end to an arm 30 extending rearwardly from the controlling rock shaft 6. 20 A helical spring 31 secured at one end to the bell crank lever 23 and at the opposite end to the upper end of the arm 25 functions to swing the bell crank lever 23 clockwise and thus to move the shuttle feeler 25 support with the shuttle feeler thereon rearwardly while at the same time permitting the shuttle feeler support to have a swinging or rotary movement on its axis. Normally the parts stand in the position shown 30 in Fig. 1. Upon the call for filling replenishment the controlling rock shaft 6 is rotated to elevate the arm 30 against the action of the spring 32 and thus raise the link 29 and permit the spring 31 to function. 35 This construction and operation is all more fully set forth in the before mentioned patent to Davis.

The filling clamping and parting means 40 are preferably movable with and preferably carried by the shuttle feeler. These means include the fixed clamping blade 33, the fixed cutting blade 34, the movable clamping blade 35 and the movable cutting blade 36. The movable blades move together and 45 are pivoted on the pin 37. One of these blades as the blade 36 is provided with an upwardly projecting ear 38. As the shuttle feeler nears the end of its rearward movement this ear contacting with a pin 39 at 50 the end of the guide bar 17 swings the movable blades to open position as shown in Fig. 2.

A movable and preferably a yielding actuator is provided for effecting the closing of 55 the filling clamping and parting means and this actuator is preferably supported from the loom frame independently of the shuttle feeler and is given its actuating movement by means carried by and movable on the 60 lay.

In the preferred construction illustrated 65 an actuator supporting bracket 40 is secured to some fixed part of the loom such for example as a rearwardly extending projection 41 of the feeler supporting bracket 21

and is shown as held in place by a bolt 42. The bracket 40 is preferably ribbed at 43 to fit into a correspondingly grooved portion of the projection 41 and thus prevent the bracket from turning. A stub shaft 44 70 is rigidly mounted by means of the set screw 45 in a horizontally projecting hub 46 of the actuator bracket 40. The actuator 47 is journaled on the stub shaft 44 and comprises a depending arm 48 having a lateral projection 49 at its lower end and a rearwardly projecting arm 50 which is preferably constituted as a thin spring metal blade clamped in place by a set screw 51. The actuator is maintained with the arm or 80 blade 50 in elevated position by a helical spring 52 surrounding the stub shaft in a pocket in the bracket 40 and fastened at one end to the bracket and at the other end to the actuator. The upward movement of the 85 actuator is limited by a shoulder 53 thereon contacting with the shoulder 54 on the bracket.

The movement of the actuator to effect closing of the filling clamping and parting 90 means and the movement of the transfferer to effect replenishment are effected by means mounted upon the lay and brought into operative position by the shuttle feeler when the shuttle feeler has indicated that the shuttle 95 is properly boxed at the transfer end of the loom after the call for filling replenishment.

In the construction illustrated the shaft 12 journaled in the bearing block 13 on the face of the lay has secured thereto in addition to the bunter 11 a positioner 55 and a trip 56. The bunter 11 co-operates with the dog 10 on the transfferer as already described; the positioner 55 co-operates with a heel 57 depending from the shuttle feeler; and the trip 56 co-operates with the lateral projection 49 of the depending arm 48 of the actuator. A helical spring 58 on the shaft 12 engaging the positioner 55 at one end and the bearing block at the other end 100 acts normally to swing the shaft clockwise until the adjustable stop 59 carried by the bunter contacts with the bearing block and when the parts are in this position there will be no contact of the bunter, positioner 105 or trip with the dog, heel or projection when the lay beats up and consequently no wear 110 of the parts.

The parts are so constructed and adjusted 115 that when the filling in the running filling carrier in the shuttle has become exhausted or exhausted to a predetermined degree and that fact has been indicated by the usual indicating means the controlling rock shaft 6 will be rotated against the action of the 120 spring 32. Thereupon the shuttle feeler with the filling clamping and parting means carried thereon is moved rearwardly under the action of the spring 31 until the end of the sleeve 16 engages the pin 39. As this 125

movement concludes the pin 39 engaging the tail 38 swings the movable members of the clamping and parting means to open position. As the lay now beats up with the shuttle containing the exhausted filling carrier at the transfer end the shuttle feeler 14 feels for the shuttle and if the shuttle is improperly boxed so that it projects from the box the shuttle contacts with the shuttle 10 feeler and the latter is moved forwardly and there is no operation of the transerrer. If, however, the shuttle is properly boxed as the lay beats up the shuttle feeler passes the end of the shuttle and the positioner 55 15 comes into contact with the heel 57 of the rearwardly projected shuttle feeler and rocks the shaft 12 against the action of the spring 58 elevating the bunter 11 and trip 56 connected thereto into line with the dog 20 10 of the transerrer and the lateral projection 49 of the actuator respectively. As the beat up of the lay continues the positioner 55 pushes the shuttle feeler forwardly and the bunter 11 engaging the dog 10 actuates 25 the transerrer in the usual manner to transfer a fresh filling carrier from the hopper into the shuttle and eject the exhausted filling carrier therefrom and the trip 56 coming into contact with the projection 49 of 30 the actuator swings the actuator about its pivot 44 bringing the spring blade arm 50 into contact with the top edge of the movable cutting blade 36 and swinging this blade and the connected movable clamping 35 blade downwardly thus clamping and parting the filling extending from the abandoned filling carrier through the eye of the shuttle to the fell of the cloth. Thereafter the parts under the action of the springs 32, 52 40 and 58 return to their normal positions as illustrated in Fig. 1.

Having fully described my invention, what I claim as new and desire to secure by Letters Patent is:—

45 1. An automatic filling replenishing loom comprising a lay, a hopper for the fresh filling carriers, a transerrer for transferring a fresh filling carrier from the hopper to the lay, a shuttle feeler, filling clamping and parting means mounted on the shuttle feeler, a movable actuator for closing said filling clamping and parting means, a positioner and a trip movably mounted on the lay, means acting upon the call for filling 50 replenishment to move the shuttle feeler rearwardly and if the shuttle be properly boxed to bring the shuttle feeler into position to be struck by the positioner and thereby cause the trip to be moved into line with 55 the actuator, and means for actuating the transerrer upon the beat up of the lay with the parts thus positioned whereby upon the actuation of the transerrer and upon the conclusion of the beat up of the lay the 60 actuator will be actuated to close the filling 65

clamping and parting means to clamp and part the filling of the exhausted filling carrier.

2. An automatic filling replenishing loom having the construction defined in claim 1 70 in which the movable actuator is supported on the loom frame independently of the shuttle feeler.

3. An automatic filling replenishing loom having the construction defined in claim 1 75 in which the positioner and the trip are both connected to a shaft journaled on the lay.

4. An automatic filling replenishing loom having the construction defined in claim 1 80 in which the said movable actuator has a yielding contact with the filling clamping and parting means in effecting the closure thereof.

5. An automatic filling replenishing loom comprising a lay, a hopper for the fresh filling carriers, a transerrer for transferring a fresh filling carrier from the hopper to the lay, a dog connected to the transerrer, a shuttle feeler, filling clamping and parting means mounted on the shuttle feeler, a movable actuator for closing said filling clamping and parting means, a bunter movably mounted on the lay, a positioner and a trip both movable with the bunter, means acting upon the call for filling replenishment to move the shuttle feeler rearwardly and if the shuttle be properly boxed to bring the shuttle feeler into position to be struck by the positioner and thereby cause the bunter to be moved into line with the transerrer 90 dog and the trip into line with the actuator whereby upon the beat up of the lay the transerrer will be actuated to transfer a filling carrier from the hopper to the lay and the actuator will be actuated to close the filling clamping and parting means to clamp and part the filling of the abandoned filling carrier. 100

6. An automatic filling replenishing loom having the construction defined in claim 5 110 in which the movable actuator is supported on the loom frame independently of the shuttle feeler.

7. An automatic filling replenishing loom having the construction defined in claim 5 115 in which the positioner and the trip are both connected to a shaft journaled on the lay.

8. An automatic filling replenishing loom having the construction defined in claim 5 120 in which the said movable actuator has a yielding contact with the filling clamping and parting means in effecting the closure thereof.

9. An automatic filling replenishing loom comprising a lay, a hopper for the fresh filling carriers, means for transferring a fresh filling carrier from the hopper to the lay, a shuttle feeler, filling clamping and parting means, and means, operatively positioned by the shuttle feeler when the shuttle is prop- 125 130

- erry boxed at the transfer end of the loom, to actuate the filling clamping and parting means to clamp and part the filling of the filling carrier to be abandoned.
5. 10. An automatic filling replenishing loom comprising a lay, a hopper for the fresh filling carriers, means for transferring a fresh filling carrier from the hopper to the lay, a shuttle feeler, filling clamping and parting 10 means, and yielding means, operatively positioned by the shuttle feeler when the shuttle is properly boxed at the transfer end of the loom, yieldingly to actuate the filling clamping and parting means to clamp and part the 15 filling of the filling carrier to be abandoned.
11. An automatic filling replenishing loom comprising a lay, a hopper for the fresh filling carriers, means for transferring a fresh filling carrier from the hopper to the lay, a 20 shuttle feeler, filling clamping and parting means, means carried by and movable on the lay for effecting the closing movement of the filling clamping and parting means, and means carried by the shuttle feeler acting
- to move to operative position said means 25 carried by the lay when the shuttle feeler has indicated proper boxing of the shuttle at the transfer end of the loom.
12. An automatic filling replenishing loom comprising a lay, a hopper for the fresh filling carriers, means for transferring a fresh filling carrier from the hopper to the lay, a shuttle feeler, filling clamping and parting 30 means, a movable actuator for closing said filling clamping and parting means, means 35 movably mounted on the lay acting when moved into operative position to actuate the transferring means and the said actuator upon the beat up of the lay, and means carried by the shuttle feeler acting to move said 40 means on the lay into operative position when after call for filling replenishment the shuttle feeler has indicated the proper boxing of the shuttle at the transfer end of the 45 loom.

In testimony whereof, I have signed my name to this specification.

UBALD HEBERT.
